UNITED STATES PATENT OFFICE.

GEORGE L. WALKER, OF NEW YORK, N. Y., ASSIGNOR TO AIR REDUCTION COMPANY, INC., A CORPORATION OF NEW YORK.

BLOWPIPE.

1,310,102.

Specification of Letters Patent. Patented July 15, 1919.

Application filed February 5, 1919. Serial No. 275,193.

To all whom it may concern:

Be it known that I, GEORGE L. WALKER, residing at New York city, in the county of New York, State of New York, have invented certain new and useful Improvements in Blowpipes; and I do hereby declare the following to be a full, clear, and exact description of the invention, such as will enable others skilled in the art to which 5 it appertains to make and use the same.

This invention relates to blowpipes employing combustible and oxidizing gases under pressure and capable of producing high temperature flames employed in various 15 heating operations.

The object generally of my invention is to provide a blowpipe structure of relatively simple character, in which interchangeable tips of varying dimensions provide for individually 20 regulated proportioning of the gases and form with the head, when the parts are assembled, a substantially gas-tight joint which prevents leakage of the gases.

25 A further object of my invention is the provision of a blowpipe, in which the interchangeable tips are constructed to regulate the supply of one of the gases whereby a proper proportioning of the mixture is assured, without resort to ducts or passages 30 of small diameter which may become partially closed by accumulation of deposited carbon or dirt.

Further objects and advantages of my invention will be apparent as it is better understood, by reference to the following specification when read in connection with accompanying drawing in which—

Figure 1 is a longitudinal section through 40 the head and tip of a blowpipe embodying my invention.

Fig. 2 is a section on the line 2—2 of Fig. 1.

Fig. 3 is a view in perspective of the tip. 45 Blowpipes have been heretofore constructed in which combustible gas is delivered to the discharge passage of the tip through inlet ducts of relatively small diameter, drilled in the rear ends of the tip. 50 Such inlet ducts are closed except at the end, so that deposited carbon or shop dust may readily accumulate therein, gradually reducing the effective area of the ducts and seriously impairing the efficiency of the 55 blowpipe by changing the proportioning of

the mixture. This may proceed, unnoticed by the workman, until the blowpipe refuses to function, when the ducts are generally cleaned with some difficulty owing to their relatively small diameter.

I have devised a structure which provides for proper proportioning of gases and obviates the necessity of employing ducts of relatively small diameter, the proportioning being nevertheless varied by the mere substitution of a tip capable of producing a flame of the required size. My structure, moreover, provides a gas-tight joint between the tip and head to prevent the escape of gases other than through the discharge 70 passage in the tip. The blowpipe herein-after described has therefore certain advantages over similar devices heretofore employed, which commend it to users of such devices.

Referring to the drawing, 5 indicates a head having passages 6 and 7 for oxidizing and combustible gases respectively, the gases being supplied through pipes 8 and 9 from suitable sources. The passage 6 terminates 80 at the apex of a conical projecting seat 10. An annular channel 11 in the seat 10 surrounds the end of the passage 6 and the passage 7 terminates therein.

A tip 12 having a discharge passage 13 is 85 adapted to be secured to the head 5 by means of a nut 14 and is provided at its inner end with a recessed surface conforming to the outer edge of the seat 10 and forming therewith a substantially gas-tight joint. The 90 recessed surface at the inner end of the tip 12 is countersunk adjacent the inlet to the discharge passage and extending outwardly to the outer periphery of the channel 11, so that an annular space is provided between 95 the seat 19 and the inner end of the tip, except at the outer edge or sealing portion of the seat. Preferably a channel 15 coöperating with the channel 11 in the head, is formed in the countersunk surface.

The depth of the countersunk surface is carefully designed to provide sufficient space between such surface and the seat 10, to permit the passage of the desired quantity of gas from the channel 11 to the inlet to the 10 discharge passage 13, where it mixes with the gas issuing from the passage 6 in the head. The depth of the countersunk surface will therefore vary in tips of different dimensions, intended to provide flames of 110

varying sizes, and requiring different proportioning of the gases. By simply removing a tip of given size and substituting another of desired size the user may employ 5 flames of different dimensions, the gas being automatically supplied in proper proportions regulated by the distance between the countersunk surface and the seat 10.

As will be at once apparent, the proportioning is accomplished without employing ducts or passages capable of retaining deposited carbon or dirt. The countersunk surface may be readily wiped clean and a glance assures the user that the blowpipe is 15 in suitable condition to operate efficiently. Leakage of gas and escape thereof except through the discharge passage is impossible because of the coöperation of the outer edge of the recessed surface of the tip with the 20 corresponding portion of the conical seat 10.

The simplicity of the structure above described and the obvious ease with which it may be maintained in a highly efficient condition renders it adaptable for use by relatively unskilled workmen. Such persons may ruin blowpipe tips, of the previously known form employing closed ducts or passages for proportioning the gas delivered to the discharge passage of the tip, by inadvertently reaming and enlarging the ducts in attempting to remove accumulated dirt therefrom. With the construction herein defined, dirt does not readily accumulate and such as may appear on the countersunk 35 surface may be simply wiped off. Tips constructed in accordance with my invention should therefore continue to give satisfactory and efficient service for indefinite periods.

40 Various changes may be made in the form, arrangement, and construction of the parts without departing from the spirit of the invention or sacrificing any of its material advantages, the form hereinbefore described 45 being merely the preferred embodiment thereof.

I claim:

1. In a blowpipe the combination of a head having a seat and oxidizing and combustible gas passages terminating therein, and a tip having a discharge passage and a surface coöperating with said seat to form a gas-tight joint surrounding the ends of the oxidizing and combustible gas passages, said 50 surface being countersunk within said joint and thereby spaced from said seat whereby gas from one of the passages in said head is permitted to flow to and mix with the gas issuing from the other passage in said head 55 at the inlet to said discharge passage.

2. In a blowpipe the combination of a head having a projecting conical seat and oxidizing and combustible gas passages terminating therein, and a tip having a discharge passage and a recessed surface co-

operating with said seat to form a gas-tight joint surrounding the ends of the oxidizing and combustible gas passages, said surface and seat being spaced within said joint whereby the gas from one of the passages in 70 said head is permitted to flow to and mix with the gas issuing from the other passage in said head at the inlet to said discharge passage.

3. In a blowpipe the combination of a 75 head having a projecting conical seat and oxidizing and combustible gas passages terminating therein, and a tip having a discharge passage and a surface coöperating with said seat to form a gas-tight joint surrounding the ends of the oxidizing and combustible gas passages, said surface being countersunk within said joint and thereby spaced from said seat whereby gas from one 80 of the passages in said head is permitted to flow to and mix with the gas issuing from the other passage in said head at the inlet to said discharge passage.

4. In a blowpipe the combination of a head having oxidizing and combustible gas 90 passages, and a seat having an annular channel therein, one of said passages terminating in said seat and the other in said channel, and a tip having a discharge passage and a surface coöperating with said seat to form a 95 gas-tight joint surrounding said channel, said surface and seat being spaced between said channel and discharge passage whereby gas from said channel and the passage terminating therein is permitted to flow to 100 and mix with the gas issuing from the other passage in said head at the inlet to said discharge passage.

5. In a blowpipe the combination of a head having oxidizing and combustible gas 105 passages and a projecting conical seat having an annular channel therein, one of said passages terminating at the apex of said seat, and the other in said channel, and a tip having a discharge passage alining with 110 one of the gas passages in said head and a recessed surface coöperating with said seat to form a gas-tight joint surrounding said channel, said surface being countersunk within said joint and thereby spaced from said 115 seat whereby gas from said channel and the passage terminating therein is permitted to flow to and mix with gas issuing from the other passage in said head at the mouth of said discharge passage.

6. In a blowpipe the combination of a head having oxidizing and combustible gas passages and a projecting conical seat having an annular channel therein, one of said 120 passages terminating at the apex of said seat and the other in said channel, and a tip having a discharge passage alining with one of the passages in said head, a recessed surface coöperating with said seat to form a gas-tight joint surrounding said channel, 125 130

said surface having a channel coöperating with the channel in said head and said seat and surface being spaced within said channels whereby the gases from said head are permitted to mix at the inlet to said discharge passage.

7. In a blowpipe, the combination with a head having a seat and oxidizing and combustible gas passages, of a tip having a surface coöperating with said seat to form a gas tight joint surrounding the ends of said passages, a discharge passage, a recess communicating with said discharge passage, means for conveying gas from one of the passages in said head to said recess, the other passage in said head communicating directly with said recess and a nozzle supported on said head independently of said tip and projecting into said recess.
8. In a blowpipe the combination with a head having a projecting conical seat and oxidizing and combustible gas passages, of a tip having a surface coöperating with said seat to form a gas tight joint, surrounding the ends of said passages, a discharge passage, a recess communicating with said discharge passage and means for conveying gas from one of the passages in said head to said recess, the other passage in said head communicating directly with said recess.
9. In a blowpipe, the combination with a head having a conical seat, oxidizing and combustible gas passages, and a projecting nozzle in which one of said passages termi-

nates, of a tip having a surface coöperating with said seat to form a gas tight joint surrounding the ends of said passages, a discharge passage, and a recess communicating with said discharge passage and with the other passage in said head, said nozzle projecting into said recess when said tip is assembled with said head.

10. In a blowpipe, the combination with a head having a projecting conical seat, oxidizing and combustible gas passages and a nozzle at the apex of said seat forming the outlet for one of said passages, of a tip having a surface coöperating with said seat to form a gas tight joint surrounding the ends of said passages, a discharge passage, and a recess communicating with the other passage in said head, said nozzle projecting into said recess when said tip is assembled with said head.

11. In a blowpipe, the combination with a head having oxidizing and combustible gas passages, and a projecting nozzle forming the outlet from one of said passages, of a tip having a discharge passage, a recess at its inner end embracing said nozzle, and means for maintaining a predetermined ratio of the gases flowing to said recess, said tip and head having coöperating conical surfaces to prevent the escape of gases other than through said discharge passage.

In testimony whereof I affix my signature.

GEORGE L. WALKER.
